UNITED STATES PATENT OFFICE.

PERLEY R. GLASS, OF BROOKLINE, MASSACHUSETTS, ASSIGNOR TO UNITED SHOE MACHINERY CORPORATION, OF PATERSON, NEW JERSEY, A CORPORATION OF NEW JERSEY.

FRENCH-BINDING STRAIGHTENING AND CEMENT-APPLYING MACHINE.

1,395,270.

Specification of Letters Patent.

Patented Nov. 1, 1921.

Application filed October 2, 1919. Serial No. 327,983.

To all whom it may concern:

Be it known that I, PERLEY R. GLASS, a citizen of the United States, residing at Brookline, in the county of Norfolk and 5 State of Massachusetts, have invented certain Improvements in French-Binding Straightening and Cement-Applying Machines, of which the following description, in connection with the accompanying drawings, 10 is a specification, like reference characters on the drawings indicating like parts in the several figures.

This invention relates to machines for use in the manufacture of boots and shoes and 15 is herein illustrated as embodied in a machine used in the production of a so-called French edge.

It is customary in the manufacture of certain styles of boots and shoes to bind the 20 edges of parts of uppers with strips of fabric. To this end such a strip is stitched to the edge of the vamp, quarter or other piece of the upper, cement is applied to the strip, and the free portion of the strip folded 25 about the edge of the vamp or other piece and pressed down so that the cement will hold its firmly in place.

Hitherto there have customarily been three distinct steps in the formation of the 30 French edge after the binding has been stitched to the material. First the free portion of the binding is wiped over that portion of itself which is attached to the material until the stitches "smile," that is, until 35 they can be plainly seen. This operation is known as straightening the binding, since it leaves the free portion of the binding extending out from the edge of the material to which the binding is attached in a plane 40 which is substantially a continuation of the plane of the display surface of the material. A machine for thus straightening the binding is shown and described in Patent No. 1,322,591, granted November 25, 1919. 45 The second step comprises applying a coating of cement to the margin of the material and to one side of the straightened binding strip. This has commonly been done by a hand brush. The third step is to fold the 50 free portion of the strip over upon the material and press it into place, a machine by which this step may be accomplished being

described in the patent to McIntire No. 1,278,490, of Sept. 10, 1918.

The general object of the present invention is to provide a machine by which the first two steps, or two operations of similar nature, may be accomplished simultaneously. According to one feature of the present invention, the piece of work comprising 60 a piece of material to which a binding or similar member has been attached is subjected in one operation to the action of a binding-engaging member which manipulates the binding and to an adhesive applying mechanism. The illustrative machine pulls out or straightens the binding strip in substantially the same manner as that of the application filed in the name of McIntire, the adhesive material being applied 65 by a specially constructed feed roll to which cement is supplied.

This and other features of the invention, including certain details of construction and combinations of parts will be described as 70 embodied in an illustrative machine and pointed out in the appended claims.

Referring now to the accompanying drawings,

Figure 1 is an elevation of a machine in 80 which the present invention is embodied;

Fig. 2 is a perspective of the elements of the machine which operate upon the work, and of the cement receptacle;

Fig. 3 is a section of a portion of the 85 roll and work showing more particularly the application of cement to the work;

Fig. 4 is a perspective showing a piece of work being operated upon;

Fig. 5 is an end view of the roll and the 90 casing which contains it, and

Fig. 6 is a section on the line 6 of Fig. 1. The illustrative machine, except for the cement applying mechanism, is substantially like the machine of the McIntire patent. 95

Before proceeding to a description of the cement applying mechanism, the other parts of the machine will be briefly outlined. Fast to a rotary shaft 7 is a grooved pulley 9 which may be clutched at any time to a continuously running driving pulley 11 by depressing a treadle (not shown) connected to a treadle-rod 13. A belt 15 running around the pulley 9 over guide pulleys 10 and

around a pulley 12 serves to rotate the binding engaging member 17 which is in the general form of a disk is resiliently mounted and operates to wipe or pull out the binding. 5 The roll 19 is fast to a shaft 20 which is driven at a reduced speed from the shaft 7 by two chains 21 and 23 and suitable sprockets. The chain 21 runs around a sprocket on the shaft 7 and around a 10 sprocket located at one end of a short horizontal shaft the bearing of which is shown at 22. At the right-hand end of this short shaft is a second sprocket, the chain 23 running around this last-named sprocket and around 15 a sprocket fast to the right-hand end of the shaft 20. The feed disk 25 is mounted at the lower end of a substantially upright shaft and is driven by belts 27 and 29 and suitable pulleys. A bar 31 having a fork 20 which is located beneath a collar on the substantially upright shaft of the wiper 17 is adapted to prevent the feed disk from being lifted into contact with the wiper 17. The directions of rotation of the roll, disk and 25 wiper are shown in Fig. 2.

Referring now to Fig. 4, the operation of the machine, as thus far described, is as follows: The work consists of a piece of sheet material 100 to which a strip of binding 200 has been attached by a line of 30 stitches which runs parallel and close to the registering edges of the material and fabric. The operator bends one end of the fabric strip about its line of attachment and 35 presents the work to the machine as shown in Fig. 4. Thereafter the work is fed through the machine by the coöperation of the margin of the feed disk 25 with the cylindrical left-hand end portion of the roll, 40 and the binding is "straightened," that is, the free portion is bent over that portion of itself which is attached to the material 100. The machine, as thus far described and its mode of operation, is substantially 45 the same as that of the McIntire patent and will not be described further in detail. It will be understood that the work, as it comes from the McIntire machine, is ready to be cemented preparatory to the folding of the 50 binding about the edge of the material.

Hitherto it has been customary to cement the work by a hand brush or in any event to apply the cement in a separate operation.

According to the present invention the cement is applied simultaneously with the straightening of the binding. In the illustrative machine this is accomplished by a special construction of the feed roll to which cement is supplied from a reservoir. The 55 roll has the usual cylindrical portion which, with the feed disk 25, coöperates in feeding the work. Located inside (to the right of) this feeding portion is a stepped portion comprising a corrugated step 33 of larger 60 diameter than the cylindrical portion and a

second corrugated step 35 of less diameter than the step 33. The functions of the step 33 are to support the work for the operation of the wiper 17, and to apply cement to the under side of the margin of the material 70 100. The function of the step 35 is to apply cement to the under side of the straightened strip 200 as shown in Fig. 3. Located to the right of the step 35 is a smooth hub 37 upon which the surplus cement falls and 75 from which it is removed by a scraper 39, adjustably held in place by a screw 41, and returned to the main body of cement in a passageway 43. The thickness of the layer of cement carried by the step 33 is regulated 80 by a doctor 45 which is adjustable by means of a screw 47. Cement is supplied to the roll from a reservoir 49 having a pivoted cover 51 which may be held closed by a thumb screw 53. This reservoir has an outlet in 85 the form of the passageway 43, which has been referred to above, and terminates in the lower portion of a casing 55. This casing is generally circular in cross-section, the top being cut away to permit the roll to protrude from it. At the outer end of the casing is a closure or cap 57 having an annular rib 59 which fits closely about the end feeding portion of the roll so as to keep it free from cement. Mounted in the rib is a felt 90 wiper 61 which keeps any cement which may get upon the feeding portion of the roll from rising into contact with the under side 95 of the work.

It will be noted that only a comparatively 100 thin layer of cement is permitted to be carried up to the main portion 100 of the work by the step 33 but that the step 35 is permitted to carry all that will adhere to it. When a cylindrical or substantially cylindrical roll is used not enough cement is applied to the binding. It has been found by experiment that by providing a step, such as 35, of less diameter than that of the work-supporting step 33, the binding is properly 110 cemented. The step 35 carries at all times a thick layer of cement such that the binding need merely touch it lightly to receive the requisite amount.

Assuming that the work comprises a piece 115 of leather 100 to the grain side of which a strip of fabric binding 200 has been stitched, the work is fed through the machine grain side up, as has been described above and as shown in Fig. 4, the wiper 17 operating to pull out or straighten the binding, and the roll operating to apply a coating of cement to the margin of the flesh side of the leather and to the under side of the projecting portion of the binding.

Although in the illustrative machine the roll 19 has been constructed so that different parts of it serve the functions of work feeding, work supporting and cement applying, and although such a structure possesses 120 130

advantages in compactness and simplicity, it should be understood that the invention is not limited in its broader aspects to work feeding, work supporting and cement applying mechanism interrelated in this manner.

Having thus described my invention, what I claim as new and desire to secure by Letters Patent of the United States is:

1. A machine for operating upon a piece 10 of work which consists of a piece of sheet material to which a flexible strip is attached by a row of stitches, having in combination, means for operating upon the strip to bend its free portion about the row of 15 stitches, and means for applying an adhesive to the work.

2. A machine for operating upon a piece of work which consists of a piece of sheet material to which a strip of fabric is attached by a row of stitches, having in combination, means for bending the strip more than ninety degrees about its line of attachment, and means for applying an adhesive to the work.

25 3. A machine for operating upon a piece of work which consists of a piece of material to which a strip of binding is attached, having in combination, means for supporting the work, means for wiping the free portion 30 of the binding over that portion of itself which is attached to the material, and means for applying an adhesive to the work.

4. A machine for operating upon a piece of work which consists of a piece of material 35 to which a strip of binding is attached, having in combination, a binding-engaging member, means for causing said member to pull a portion of the binding over that portion of itself which is attached to the material, and means for applying an adhesive to the work.

5. A machine for operating upon a piece of work which consists of a piece of material to which a strip of binding is attached, having in combination, a resilient binding-engaging member, means for causing said member to pull a portion of the binding over that portion of itself which is attached to the material, and means for applying an adhesive to the work.

6. A machine for operating upon a piece of work which consists of a piece of material to which a strip of binding is attached, having in combination, means for feeding the 55 work, means for progressively wiping the free portion of the binding over that portion of itself which is attached to the material, and means for applying an adhesive to the work.

60 7. A machine for operating upon a piece of work which consists of a piece of material to which a strip of binding is attached, having in combination, means for feeding the work, a binding-engaging member having an operative portion adapted to move

over that side of the work to which the binding is attached, means for actuating said member to cause it to separate the free portion of the binding from the work and to draw said free portion over the portion 70 which is attached to the work, and means for applying an adhesive to the work.

8. A machine for operating upon a piece of work which consists of a piece of material to which a strip of binding is attached, having in combination, means for supporting the work, a substantially flat-faced member for wiping the free portion of the binding over that portion of itself which is attached to the material, and means for applying an 80 adhesive to the work.

9. A machine for operating upon a piece of work which consists of a piece of material to which a strip of binding is attached, having in combination, means for feeding the 85 work, a member rotating in a path approximately parallel to the plane of the work and operating to turn the free portion of the binding substantially 180° about its line of attachment, and means for applying an adhesive to the work.

10. A machine of the class described, having in combination, a feed roll, means for rotating the roll about a substantially horizontal axis, a wiping member in the form of a disk, means for rotating the wiping member about a substantially vertical axis, and cement applying mechanism between which and the wiper the work is fed.

11. A machine for applying adhesive to a 100 piece of work which comprises a piece of sheet material to which a strip of binding is attached having, in combination, a cement applying roll having a plurality of steps thereon including a step of greater diameter 105 than any other and, located at one side of this step, another step of lesser diameter, and means for feeding the work over the roll with the margin of the sheet material in contact with the step of greater diameter 110 and the free portion of the binding overhanging the step of lesser diameter.

12. A machine for applying adhesive to a piece of work which comprises a piece of sheet material to which a strip of binding is 115 attached having, in combination, a cement-applying roll the cement-applying portion of which consists entirely of two steps, and means for feeding the work over the roll with the margin of the sheet material in contact 120 with the step of greater diameter and the free portion of the binding strip overhanging the step of lesser diameter.

13. A machine of the class described, having in combination, a stepped roll over which the work is fed, means for supplying an adhesive to the steps, and means for feeding the work over the roll in such manner that the work contacts with one step only and overhangs an adjacent step.

- 4
14. A machine of the class described, having in combination, a rotary roll having steps formed theron, a receptacle for cement arranged to supply an adhesive to the roll, means for regulating the thickness of the layer of adhesive carried by one of the steps while permitting the adhesive to accumulate freely upon the other step, and means for feeding the work over the roll.
15. A machine for applying adhesive to a piece of work which comprises a piece of sheet material to which a strip of binding is attached, having in combination, a work sup-
- port in the form of a stepped roll, means for supplying adhesive to the steps respectively in different quantities, and means for feeding the work over the roll with the margin of the material resting upon that step to which the lesser quantity is supplied and the strip of binding overhanging that step to which the greater quantity is supplied.
16. In testimony whereof I have signed my name to this specification.

PERLEY R. GLASS.
